PORTRABLE ONE WAY COIN OPERATED TELEPHONE FOR INSTITUTIONS AND HOSPITALS

Susan M. Peoples, 701 Portland St.,
Baltimore City, Md. 21230

Filed Jan. 31, 1968, Ser. No. 10,382

Term of patent 14 years

Int. Cl. D14—03

U.S. Cl. D26—14

FIG. 1.

FIG. 2.

FIG. 3.

FIG. 4.

FIGURE 1 is a perspective view of a portable one way coin operated telephone for institutions and hospitals showing my new design;

FIGURE 2 is a top plan view;

FIGURE 3 is a side view; and

FIGURE 4 is a front view thereof.

The rear of the article is plain.

I claim:

The ornamental design for a portable one way coin operated telephone for institutions and hospitals, as shown and described.
